CABINET FOR A COIN-CONTROLLED AMUSEMENT MACHINE

Joseph E. Lally, McHenry, and Terrence A. Reedy, Jr.,
Skokie, Ill., assignors to Bally Manufacturing Corporation,
Chicago, Ill.

Filed July 14, 1971, Ser. No. 162,737

Term of patent 14 years

Int. Cl. D21—03

U.S. Cl. D34—5

FIG. 1 is a front perspective view of a cabinet for a coin-controlled amusement machine showing our new design;

FIG. 2 is a front elevational view thereof;

FIG. 3 is a right side elevational view thereof;

FIG. 4 is a top plan view thereof.

The rear is substantially plain and unornamented.

We claim:

The ornamental design for a cabinet for a coin-controlled amusement machine, as shown and described.
